UNITED STATES PATENT OFFICE.

JOSEPH A. HOLIFIELD, OF MOBILE, ALABAMA, ASSIGNOR TO WHITE FUEL OIL ENGINEERING CORPORATION, OF NEW YORK, N. Y., A CORPORATION OF NEW YORK.

ARC-WELDING APPARATUS.

Application filed May 9, 1921, Serial No. 467,844. Renewed June 29, 1923.

To all whom it may concern:

Be it known that I, JOSEPH A. HOLIFIELD, a citizen of the United States of America, residing at Mobile, in the county of Mobile and State of Alabama, have invented certain new and useful Improvements in Arc-Welding Apparatus, of which the following is a specification.

This invention relates to an arc welding apparatus and contemplates certain modifications in the design and operation of the arc welding system utilizing a twin field type of self-regulating generating apparatus for the welding current, which forms the subject matter of my pending application, Serial No. 454,277, filed the 21st day of March, 1921, wherein I disclose an armature having a single commutator and twin independent sets of fields separately and differentially excited which are adapted simultaneously and jointly to exert the sum of the difference of their magnetic influences upon the same windings of the armature to both generate and automatically regulate the current delivered to the welding circuit to maintain a substantially constant wattage or current at the arc.

The object of my present invention is to provide the set of fields, whose magnetic influence varies responsive to the resistance in the arc, with compound differentially connected windings to the end that before the arc is struck both sets of fields will have like polarity and exert accumulatively the sum of their magnetic influence on the armature so as to give it a high voltage under such open circuit conditions. When the arc is struck, the flow of the welding current will reverse the polarity of the variable set of fields and at the same time short circuit the terminals of the accumulative windings thereof so that the twin sets of fields now act differentially, the one set opposing the other with the result that the magnetic influence of the twin fields on the armature now is the sum of the difference of their magnetic strength. The advantage of the higher voltage under open arc conditions with both sets of fields acting accumulatively is that when the arc is struck it will respond more instantaneously to the regulating function of the generator.

As illustrative of an apparatus for carrying my present invention into effect, reference is made to the accompanying dia-

grammatic drawings which form a part of this specification, and in which is shown a shaft 1 driven by any suitable source of power and having mounted thereon an armature 2. This armature is elongated to permit of its co-operation with twin parallel sets of fields 3 and 4 which are independent of each other and which both exert a joint magnetic influence at the same time upon the same coil of the armature windings typically illustrated at 5. The armature coil is preferably designed with a gap 6 between the independent sets of poles but this is merely a preferable design and is not essential. Current from any substantially constant potential direct current source is supplied through circuit 7 to the field windings 3 surrounding the set of poles 8, thus separately exciting this set of field with a constant potential current and giving them a constant polarity and a substantially constant magnetic strength. The generator is provided with any standard type of commutator 11 connected in any customary manner with the armature windings 5 and having its brushes 12 connected in series with the welding arc circuit 13 which includes the electrodes 14 and 15 and has in series therewith the other set of field coils 4 surrounding the poles 16. The twin parallel fields 3 and 4 are wound to have, under welding conditions, opposite polarity and they are so wound that the constantly excited fields will have a predominating magnetic influence on the armature which is opposed more or less according to the resistance in the arc by the magnetic influence of opposite polarity of the series fields, with the result that the generator will automatically induce a predetermined flow of current through the arc circuit 13 which is in proportion to the requirements at the arc, or, in other words, the sum of the joint effect of their magnetic influences on common armature windings is to generate current which will maintain the wattage substantially constant at the arc throughout its elastic limits.

I provide a differentially connected winding 17 on the set of poles 16, this winding being in a circuit 18 across the brushes 12. When the arc circuit 13 is open, the flow of current through the circuit 18 will reverse the normal polarity of the poles 16 and cause their magnetic influence to act differently with that of the fields 3 so that the

voltage of the generator will be increased. As soon as the arc is struck and the current flow commences through the fields 4, the circuit 18 will be practically short circuited and the flow of current through the fields 4 will reverse the polarity of the poles 16 so that their magnetic influence now will oppose or buck that of the fields 3 and the voltage of the machine drops but the current output is in proportion to the sum of the difference of the magnetic influence of the fields 3 and 4 and will supply a substantially uniform current at the arc within its elastic limits.

In operation, with the arc circuit open and the constant exciting current flowing through the fields 3, the fields 4 will be open circuited and current will flow through the circuit 18 and through the differential field windings 17 changing the polarity of the fields 4 so that they will act collectively with fields 3 and thereupon the generator operates with the sum of magnetic influence with both sets of fields co-operating to induce a high voltage current. Immediately on striking the arc, the current 18 is short circuited and the flow of current through the field coils 4 will reverse the polarity of said fields and set up an opposing or bucking current in the armature windings so that the current output is equal to the sum of the difference between the magnetic influence of the twin sets of poles or to the preponderance of the magnetic intensity of the constantly excited set of fields 3 over that of the set of fields 4. As the arc is drawn, the resistance in

the arc circuit increases and as a result the predominance of the fields 3 will proportionately increase over the fields 4 with a resultant proportional increase in the voltage of the current in the arc circuit and at the same time, as the resistance in the arc circuit increases, the field windings 17 become stronger and by bucking the windings 4 will further increase the predominance of the fields 3 and further increase the voltage of the current output. As a result of this operation, the generator will automatically produce in the arc circuit a current flow which will be substantially constant at the arc or which will maintain the wattage at the arc substantially constant within the normal elastic limits of the arc.

Having thus described my invention, what I claim as new and desire to secure by Letters Patent, is:

In an arc welding apparatus, an armature having a single commutator, brushes for the commutator, an arc welding circuit in series with the brushes, twin fields for the armature, a separately excited winding for one set of fields giving them a constant polarity and a substantially constant magnetic strength, and compound differentially connected windings for the other set of fields, one winding in series with the arc and the other in a circuit across the brushes.

In testimony whereof I affix my signature,
JOSEPH A. HOLIFIELD.
